PROCESS OF TREATING HYDROCARBON OILS

Albert Ramsey Nevitt, New Brunswick, N. J., assignor to Bradford Penn Refining Corporation, Clarendon, Pa., a corporation of Pennsylvania

Application June 5, 1939, Serial No. 277,417

4 Claims. (Cl. 196—54)

The present invention relates to treatment of hydrocarbon oils and particularly to the conversion of crude petroleum oils of chemically complex character into synthetic hydrocarbons of less complex character and of a more stable as well as of a more useful nature.

Special objects of the invention are to obtain such a product through treatment of crude petroleum oils with a chemical reactive agent and accelerating medium, which under certain conditions of temperature and pressure will effect decomposition and recombination of the crude petroleum into selective compounds.

A particularly important object of the invention is to accomplish the chemical conversion of petroleum oils containing large percentages of light hydrocarbons boiling within the gasoline and lighter constituent ranges into products of a more unsaturated character.

A further object of the invention is by suitable chemical treatment of crude petroleum oils of complex character containing approximately 40% of light constituents boiling within the gasoline range, to effect a combination of the lighter or the saturated undesirable constituents with the unsaturated portions, to form a stable viscous synthetic product, useful as a lubricating oil.

Other objects are to obtain from crude petroleum oils, increased yields of selective products desired, by wholly practical chemical treatment.

Additional objects and the various novel features of the invention will appear as the specification proceeds.

The drawing accompanying and forming part of the following specification is a diagram or flow sheet illustration of the invention.

The invention involves the discovery that certain mixtures of metallic salts dissolved in an excess acid solution together with metallic sulphate solutions, when injected into crude petroleum, especially those known as the paraffin base oils, found in Pennsylvania, under certain conditions of temperature and pressure, so that partial decomposition takes place, the bonds between the hydrocarbon structures will be ruptured and a reforming of the molecular structure takes place, providing release and back pressure be controlled to allow proper contact time for the selective conversion.

It has long been known that some of these hydrocarbons, especially those of the cyclic rings, such as the cyclo-paraffins and cyclo-olefines undergo changes when subjected to thermal decomposition and condensation by heat. Such type of conversion is termed "soaking" and the

process known as "polymerization." The polymerization processes convert light products which are in the gaseous state, into liquid and solid constituents of different molecular structures. The liquid portion usually consists of a mixture of polymers in the benzene series and boiling within the gasoline range. The solid portions contain peroxides and oxypolymers in the form of petroleum gums, resins, asphaltic materials, anthracene in some cases and fixed carbon in the form of coke, with liberation of hydrogen and methane. The cracking of the heavier constituents also produces these hydrocarbons under cracking temperatures and at superatmospheric pressures.

In the refining of paraffin base oils, under present known refining methods, the temperatures and pressures employed are usually below those required for cracking. This is an essential factor due to the need of the refiner to obtain the greatest possible yield of lubricants from the crude and because such hydrocarbons easily undergo thermal decomposition, especially in the presence of the lighter constituents boiling within the gasoline range and at superatmospheric pressure.

The paraffin base oils while yielding the best quality lubricants, always contain large percentages of gasoline and paraffin waxes. The gasoline derived from such crudes, containing a large percentage of the paraffin hydrocarbons, is a rather inferior motor fuel, due to its low aromatic structure and high detonating characteristics when burned in modern high compression automobile engines. Such crudes usually contain about 30% to 40% of gasoline. The balance is made up of kerosene, gas oil, lubricants, wax and petrolatum, the two latter remaining in combination with the lubricants portion.

The lubricating portion is usually composed of the three fractions, non-viscous neutral oil, viscous neutral oil and cylinder stock. These fractions contain the wax and petrolatum portions, varying in quantity usually from about 3% to 12%.

The Pennsylvania crudes with which this invention is primarily concerned, usually contain from about 3% to 5½% of solids and semi-solids. These substances are detrimental to the production of quality lubricants. Their removal is difficult, requiring much separate processing, such as solvent treating, cold settling and pressing and the like.

Some processes have been devised for converting these solid and semi-solid constituents into

other useful viscous liquid products which are then used for blending with the finished oils to improve their pour point characteristics. Certain of such methods have been quite successful in producing high flash viscous liquids which give fluidity and pumpability to waxy oils, one such instance being that known as the manufacture of Paraflow.

Difficulties and objections present in such processes have been the matters of expense resulting from cost of extraction of the basic materials, the cost of chemicals required for conversion, the cost of process filtering and the loss of starting materials. These processes are becoming more and more impractical. Originally, 15 the basic materials required were by-products and the processes were devised mainly for utilization of such by-products. The growing demand however, caused the refiner to produce them regularly, taking such materials out of the 20 category of by-products and putting them in the class of manufactured specification products.

In the practice of such methods, temperatures and pressures used in distillation and fractionation of the paraffinic base oils have been maintained below those required for cracking, at temperatures sufficiently low to prevent cracking of the lightest lubricating constituent. This was because of the fact that if temperature rises to the cracking point, decomposition of the lubricating fractions ensues, with consequent formation of light gasoline fractions and production of carbureted gaseous compounds, which react again with the heavier constituents to form further decomposition products in the nature of 35 benzene, gasoline and low flash recycle stocks, the cyclic hydrocarbons undergoing partial polymerization into oxypolymers with much gum formation and carbon deposition. Increasing pressures cause further saturation and polymerization, with subsequent loss of all lubricating components of the crude.

Study of the reactions occurring in the above mentioned methods has led to the present invention, wherein the disadvantages are turned to 45

back pressures, the latter by way of general example, being for instance, a back pressure of 150 lbs. per square inch, with a release pressure of about 40 to 60 lbs. per square inch.

5 The aqueous vapors issuing from the release are subjected to gradual cooling and separation and the resulting synthetic material is fractionated into more or less conventional products.

10 As a specific example, a crude charging stock from the Bradford District field of Pennsylvania was used having the following specifications:

good advantage for the production of a synthetic hydrocarbon, which can be fractionated to give increased yields of high quality wax free selective lubricants.

The invention involves a treatment consisting of subjecting a mixture of crude petroleum and chemical solution to gradually increasing temperature and pressure conditions up to a point of decomposition, according to analysis of the charge and product desired to obtain, then subjecting to temperature and pressure drop in an enclosed zone and injecting a further quantity of chemicals and then increasing temperature for a predetermined period, sufficient to effect complete reaction.

The contact time is an important factor in effecting the reaction as are also the release and

60 The chemical solution was prepared as follows: 400 grams of copper sulphate and 100 grams of aluminum sulphate were weighed out, thoroughly ground to fine powder and digested in 1000 cc. of concentrated hydrochloric acid.

65 A second solution was made up of reduced cobalt acetate 75 grams, sodium nitrate 15 grams, sodium chloride 15 grams, digested in 1000 cc. hydrochloric acid.

70 The two solutions were mixed together and diluted with 1000 cc. concentrated hydrochloric acid and filtered. To this was then added 122 kilograms of water at 60° F.

75 In carrying out the treatment, with the apparatus illustrated, the crude oil and the chemical compound are transferred by pumps 1, 2, through the lines 3, 4, to a mixer 5. Surge tanks 6, 7, in

these lines under pressure from air line 8, maintain a desired steady flow of the materials. By an injector nozzle 9, the chemical solution is injected direct into the ingoing crude oil. Before this mixture is effected, the chemical solution is preferably heated to a temperature of 300° F. as by means of a heater indicated at 10, pressure being sufficient to hold it in the liquid state, up to the injector nozzle. This nozzle preferably has a relatively small bore disposed to allow the liquid to escape at high velocity into the oil stream, thus to effect a thorough intermixing with the oil before entering the heating zone.

From the mixer 5, the mixture passes by way of line 11, through the horizontally arranged series of tubes 12, in the still 13, where it is subjected to increasing temperatures up to, in the present illustration 860° F. and a contact time of 30 minutes at a pressure of about 225 lbs. per square inch. This pressure is maintained through the medium of a suitable pressure regulating valve or the like.

The heated mixture of oil and chemical solution discharges through line 14, under control of a pressure regulator valve 15 into a flash chamber 16, in an aqueous state.

heating zone or at 23, between the second heating zone and the flash chamber, or at both, or at other points, the speed of reaction can be retarded. Increasing the moisture content slows down the reaction, causing a lighter product to be formed, while decreasing the moisture content speeds up the reaction and causes a heavier and more viscous product to be formed.

In the illustration, the finished synthetic product is flashed a second time, in the chamber 24, connected with the second heating zone by piping 25. In this chamber, the product is settled hot to allow the spent metallic salts and sulphides to settle and be drawn off through the line 26. From this flash chamber, the product passes overhead through line 27, to a packed bubble tower 28, and thence through fractionating towers 29, 30 and cooler 31, to storage at 32. In this passage, the product is fractionated into more or less conventional commercial products. In the illustration, the gravity is reduced from 43.1 to 38.

A tabulation compiled from experimental runs such as given by way of example is here appended:

Breakdown of synthetic or reformed crude

Synthetic	Per cent	A.P.I. gravity	Flash	Fire	Say. vis.		Pour point, °F.	Color
					100° F.	210° F.		
Product	94	38	—	—	—	—	—	Dark green.
Summary of products:								
Gasoline	2	60.1	—	—	—	—	—	—
Kerosene	16	47.3	—	—	—	—	—	—
Gas oil	10	38.4	285	318	48	—	5-0	1½
Non vis. neut.	8	36.2	300	334	60.4	—	7-5	2
Vis. neut.	10	28.4	390	430	125	—	18/14	4
Cylinder stock	54	27.2	540	605	—	147	20/16	Dark green.

Entered in the central portion of the flash chamber is an injector nozzle 17, designed to inject at high velocity, a further supply of chemicals to complete the reaction desired. This nozzle is supplied through lines 4, 18, under control of suitable valves. For some reactions, the second injection of chemicals may be unnecessary, in which case, such valves would be entirely closed.

The temperature drop at the flash chamber 16, in the example under consideration, may be approximately 100° F., because of the location of such flash chamber outside the heating zone and because of the influx of chemical solution at nozzle 17, which exchanges heat with the hot aqueous vapors entering the flash chamber.

The gaseous mixture passes from the flash chamber 16, by way of line 19, through the vertically arranged series of tubes 20, forming the second heating zone, where decomposition temperatures in excess of 1000° F. are maintained for a contact time of approximately 30 minutes, with a discharge pressure of about 45 to 60 lbs. per square inch and a back pressure, controlled by valve 21, in excess of 100 lbs. per square inch.

In the present example, the chemical solution is injected in the mixer, for the first heating zone at the rate of 240 grains per gallon of charging stock and at the flash chamber at the same rate of 240 grains per gallon of charge, making a total of 480 grains per gallon.

This, in the process described, effects a decomposition and a recomposition of the charge, producing a heavy synthetic viscous product, differing in characteristics from the starting materials.

By the injection of steam at different points, such as at 22, between the mixer 5, and the first

40 In the reactions outlined, the wax and petro-latum portions are converted to lubricating oil fractions, thus eliminating need for the customary filtering and dewaxing steps.

What is claimed is:

1. The process of treating hydrocarbon oils, 45 which comprises subjecting a mixture of complex petroleum hydrocarbons and a chemically reactive solution containing metallic sulphates and chlorides to gradual heating and increasing pressure conditions on the order of up to 860° F. and 225 lbs. per square inch for a predetermined period of time on the order of 30 minutes, flashing the mixture under controlled pressure conditions to reduce pressure and temperature, adding a further quantity of the reactive solution, subjecting the mixture to further gradual heating in excess of 1000° F. for a predetermined period of time on the order of 30 minutes, again flashing the mixture and hot settling the spent chemical solution and fractionating and cooling the treated hydrocarbon.

2. The process of treating hydrocarbon oils, 55 which comprises subjecting a charging stock of petroleum hydrocarbon having a relatively high content of light constituents lower boiling than gas oil and higher boiling than normal hexane and a chemically reactive solution containing metallic sulphates and chlorides to gradual heating and increasing pressure conditions on the order of up to 860° F. and 225 lbs. per square inch for a predetermined period of time on the order of 30 minutes, flashing the mixture under controlled pressure conditions to reduce pressure and temperature, adding a further quantity of the reactive solution, subjecting the mixture to further gradual heating in excess of 1000° F. for

a predetermined period of time on the order of 30 minutes, again flashing the mixture and hot settling the spent chemical solution and fractionating and cooling the treated hydrocarbon.

3. The process of treating hydrocarbon oils, which comprises subjecting a paraffine base petroleum hydrocarbon and a chemically reactive aqueous solution of metallic chlorides and soluble metallic sulphates to elevated temperature at superatmospheric pressure in an enclosure for a period of time sufficient for partial decomposition of the hydrocarbon, flashing the mixture under controlled pressure conditions, separating out the spent chemical solution and fractionating and cooling the treated hydrocarbon.

15

4. The process of treating hydrocarbon oils, which comprises subjecting a paraffine base petroleum hydrocarbon and a chemically reactive aqueous solution of metallic chlorides and soluble metallic sulphates to elevated temperature at superatmospheric pressure in an enclosure for a period of time sufficient for partial decomposition of the hydrocarbon, flashing the mixture under controlled pressure conditions, injecting steam in reactive relation into the mixture at least at one point in the passage of the mixture, separating out the spent chemical solution and fractionating and cooling the treated hydrocarbon.

ALBERT RAMSEY NEVITT.
